DESIGN FOR A POT OR OTHER HOT METAL HOLDER

Harry W. Miller, Akron, Ohio

Application June 21, 1940, Serial No. 93,167

Term of patent 3½ years

To all whom it may concern:

Be it known that I, Harry W. Miller, a citizen of the United States, residing at Akron, in the county of Summit and State of Ohio, have invented a new, original, and ornamental Design for a Pot or Other Hot Metal Holder, of which the following is a specification, reference being had to the accompanying drawing forming part thereof of which:

Fig. 1 is a side elevation of a pot or other hot metal holder, showing my design;

Fig. 2 is an end elevation thereof; and

Fig. 3 is a plan view thereof.

I claim:

The ornamental design for a pot or other hot metal holder, substantially as shown.

HARRY W. MILLER.
